UNITED STATES PATENT OFFICE.

AUGUSTIN M. PRENTISS, OF ROCK ISLAND, ILLINOIS, ASSIGNOR OF ONE-HALF TO
DOUGLASS E. BULLOCH, OF WASHINGTON, DISTRICT OF COLUMBIA.

CARBURETER.

1,329,309.

Specification of Letters Patent. Patented Jan. 27, 1920.

Application filed March 6, 1917. Serial No. 152,708.

To all whom it may concern:

Be it known that I, AUGUSTIN M. PRENTISS, a citizen of the United States, residing at Rock Island, in the county of Rock Island 5 and State of Illinois, have invented certain new and useful Improvements in Carbureters, of which the following is a specification, reference being had therein to the accompanying drawing.

10 This invention relates to improvements in carbureters and has for its object:

First: To provide an improved apparatus of this nature wherein the liquid fuel is fed into the mixing chamber by positive pressure,

15 *i. e.*, a pressure greater than atmospheric.

Second: To provide a device wherein the pressure controlling the liquid feed varies with the demands of the engine.

20 Third: To provide an improved apparatus of this kind wherein the pressure on the liquid fuel is at maximum when the engine is at zero speed and is gradually diminished as the speed of the engine increases until 25 it reaches a value equal to atmospheric when the engine is at highest rated speed.

Fourth: To provide a device wherein the ratio, by weight, of liquid fuel to air is constantly maintained at a predetermined value

30 throughout all of the changes of speed of the engine.

Fifth: To provide a device which will furnish an ideal mixture at low speed, either on full open or nearly closed throttle, to 35 prevent the common tendency of motors to stall.

Sixth: To provide an improved apparatus of this nature having means for supplying air under pressure to the liquid fuel column 40 within the fuel nozzle to break up the liquid column before it issues from the fuel nozzle and thus secure an atomizing effect regardless of the variations of specific gravity in the liquid fuel.

45 The invention, with other objects and advantages thereof and the particular construction, combination and arrangement of parts comprising the same, will be understood from the following description when 50 considered in connection with the accompanying drawings forming a part hereof and wherein I have illustrated one embodiment of the invention.

In the drawings:

Figure 1 is a central vertical section of 55 a device constructed in accordance with the present invention.

Fig. 2 is a section on the line 2—2 of Fig. 1.

Fig. 3 is a section on the line 3—3 of 60 Fig. 1.

Fig. 4 is a fragmentary horizontal section on the line 4—4 of Fig. 1.

Fig. 5 is a horizontal section on the line 5—5 of Fig. 1. 65

Fig. 6 is a fragmentary vertical section of Fig. 1 of the fuel nozzle.

Fig. 7 is a fragmentary elevation of the float valve.

Fig. 8 is a diagrammatic chart illustrating 70 the theory of operation.

Fig. 9 is a fragmentary elevation of the device showing scale and index.

The invention broadly comprehends means for applying pressure upon the top 75 of the liquid fuel in the reservoir whereby the liquid fuel is caused to be fed into the mixing chamber by positive pressure which varies with the demands of the engine, the pressure being continuous and at a maximum when the engine is standing still and gradually diminishing as the speed of the engine increases. By a positive pressure is meant, in this specification, a pressure

80 greater than normal atmospheric pressure outside of the device. More particularly, the invention contemplates means for this purpose, including a piston or the like, arranged to apply pressure upon the top of the liquid fuel in the reservoir and diminish said pressure as the vacuum in the engine manifold increases in value or as the engine speeds up. The pressure which this piston applies to the top of the liquid fuel in the reservoir may be secured by means of 85

a spring element as illustrated in the drawings or by means of the weight of the piston itself by suitably loading it for the purpose, and as the chamber in which this piston works is in direct communication 90 with the engine manifold, it is readily seen that the vacuum established therein will

95 cause the piston to be raised against the action of the spring or gravity as the case may be, and result in a lessening of the 105 pressure upon the liquid fuel. When the

piston has reached the uppermost point of its travel, it uncovers a port or ports communicating with the outside atmosphere and thus establishing atmospheric pressure 5 upon the liquid fuel at this point. If, for any reason, the piston be further raised by any extraordinary degree of vacuum in the engine manifold, no further lessening of the pressure on the liquid fuel will result, 10 as the ports just mentioned are of sufficient size to insure full atmospheric pressure upon the liquid fuel.

The reasons for applying this additional positive pressure will now be explained:

15 It is well known that to secure a gaseous mixture of uniform composition, the liquid fuel component must be introduced into the air component in a high state of atomization so that a rapid and positive evaporation and 20 volatilization can take place and a perfect gaseous mixture result. To secure this atomization, an atomizing nozzle must be employed, such a nozzle consisting of an inner liquid fuel duct and an outer surrounding 25 center air duct with an adjustable perforated cap at the delivery end thereof. Further, the liquid fuel must be subjected to an air pressure so as to be fed forcibly through the fuel duct and meet the surrounding 30 current of air under pressure, at the aperture in the cap. It is to secure this atomizing effect that this additional positive pressure is applied to the liquid fuel in the reservoir so that the liquid fuel is fed into 35 the mixing chamber in a high state of atomization instead of in a continuous stream or intermittent slugs as is the case in all suction-operative devices.

It is further a well-established, though 40 little known fact, that gases do not obey the same law of efflux as liquids so that an air flow and a gasoline flow induced by common vacuum cannot be made to maintain any fixed ratio because with an increase in 45 vacuum, a greater liquid flow proportionately will result than air flow. Consequently, any fixed or ideal ratio between the two is at once destroyed. Therefore, it is proposed to make the liquid flow subject to 50 a different pressure from that inducing the air flow and to make this difference in the two pressures exactly equal at all times to that required to maintain the two flows at a fixed or ideal ratio. This point will be 55 hereinafter more fully explained.

The applicant is aware that attempts have heretofore been made to subject the liquid fuel feed to pressure, this pressure being supplied from an air pump or some equivalent element directly into the fuel reservoir but it is manifest that no such arrangement can secure the necessary control as is outlined in the paragraph just preceding. So far as the applicant is aware, no device 60 has heretofore subjected the liquid fuel in

the liquid fuel reservoir to a variable pressure which is made to follow a pre-determined law of variation and no device has heretofore employed an independent pressure upon the liquid fuel which will be 70 just sufficient to give a feed of constant proportions to the air current under all conditions of operation.

In the drawings, I have illustrated a preferred embodiment of the invention and 75 the particular construction shown comprises a casing, 1, with a central longitudinally extending chamber, 2, constituting the mixing chamber and a concentric annular chamber, 3, serving as the liquid fuel reservoir. The casing, 1, is made up of an inner cylindrical shell, 4, and an outer cylindrical shell, 5, spaced from and arranged concentric with the inner cylindrical shell, 4, and a bottom wall, 6, connecting these shells, 4 and 5. 7 is a cylindrical cap member 80 attached by means of screw threads to the upper outer part of shell, 5, and secured in position by a set screw, 9. This cap member, 7, has one or more outlet ports, 8, leading directly into the engine manifold 8. In integral with the top wall of cap, 7, are two concentric ribs 10, identical with similar ribs 12, on piston, 13, the two sets of ribs 85 serving as top and bottom seats for spring member, 11, which bears directly upon piston 13, and whose pressure thereon is regulated by screwing down cap member 7, upon the shell, 5. The annular piston 13, has channels, 14, cut in its inner and outer faces 90 for the reception of suitable packing therein so as to form a fluid-tight joint between the piston, 13, and the walls 4 and 5, of the casing 1. One or more ports, 16, are provided in outer wall, 5, of casing, 1, and positioned 105 so as to be uncovered by piston, 13, when said piston has been raised the full extent of its normal travel. This is for the purpose of admitting atmospheric pressure to the surface of the liquid fuel which is contained in chamber, 3, and which stands at the normal level indicated by the dotted line in Fig. 1.

Rotatably fitting the interior of shell, 4, is a hollow cylindrical valve member, 17, having an enlarged conical portion, 18, fitting within the flared conical portion of the casing 1. Below the conical portion, 18, is a cylindrical neck, 19, in the side walls of which are cut a plurality of apertures or 120 ports, 20, which are adapted to register upon a suitable rotation of valve member, 17, with corresponding apertures or ports, 21, in the stationary annular flange depending from the bottom wall, 6, from the casing 1. 125 The valve member, 17, is provided with a suitable opening or openings 8' in its side wall at the upper part thereof and the member has a closed upper end from which projects a stem, 58, that is suitably threaded for 130

a portion of its length for the reception of a nut, 59, and a lock nut, 60. The end of the stem, 58, is left unthreaded for attachment of the operating handle, 61. The lower end of 5 valve member, 17, is closed by means of a screw-threaded cap, 37, and suitable packing ring, 38. At the junction between the cylindrical neck, 19, and the conical portion, 18, of the valve member, 17, a channel of semi- 10 circular cross-section, 22, is cut in the outside face of valve member, 17. This channel is adapted to register with a similar channeled groove 22^a in the interior surface of the depending flange, 6, the two channels forming a continuous conduit around 15 the periphery of valve member, 17, at the junction of parts, 18 and 19, thereof. Leading from the channel, 22, are a plurality of upward inclined ducts, 23, that are bored in 20 the wall of the conical portion, 18. These ducts, 23, connect with nozzles, 24, by means of ports, 29, on the side thereof, (see Fig. 6). The conduit formed by channels, 22 and 22^a, are in connection with a conduit, 46, provided in an offset from the casing, 1, to be 25 hereinafter referred to. The nozzle, 24, consists of an outer tube, 25, and an inner tube, 26, spaced within and concentric with the outer tube, 25, and held in rigid relation therewith by suitable spider connections. 30 This tube, 26, is a liquid fuel conduit and tube, 25, is an air conduit. Tube, 26, extends beyond the end of the tube, 25, so as to be brought into juxtaposition with the aperture, 28, in the screw-threaded cap, 27, attached to tube, 25. The precise relative position of port, 28, with the end of tube, 26, is determined by the position of the lever, 31, rigidly attached to cap, 27, because of the 35 screw threaded relationship of cap, 27, and tube, 25. The position of arm, 31, is adjusted by means of the disk, 33, attached to the operating stem, 34, which carries at its lower end a knurled head, 35. The disk, 40 33, has a plurality of slots, 32, therein, as shown in Fig. 5, for the reception of the plurality of lever arms, 31, which are attached to caps, 27, and the disk, 33, is secured in any desired position by a lock nut 45 36, on the stem, 35, said stem being screw-threaded through cap, 37. It is thus seen that by this arrangement of parts, the spray nozzles, 24, are readily and easily adjusted by loosening the lock-nut, 36, and turning 50 the knurled head, 35, in either direction the desired amount and then tightening lock-nut, 36. This is for the purpose of adjusting the spray which issues from nozzles, 24, as in an ordinary atomizer. The nozzles, 24, are 55 secured in position by the screw-thread on the lower end of tube, 25, which engages similar threads in the wall of member, 17. The flow of liquid fuel through each of the atomizing nozzles, 24, is controlled by a 60 slotted port, 30, four of which are shown in this device in Fig. 3, although a greater or less number of such ports and nozzles could obviously be used without departing from the spirit of this invention. The slotted ports, 30, are, for convenience, designated, 70 30^a, 30^b, 30^c, and 30^d, in Fig. 3 and it is noted that the vertical dimensions of these ports, 30, are the same and just equal to the vertical cross-section of the oil tube, 26, (see Fig. 6), but that the horizontal dimension of 75 these slotted ports, 30, increase in an arithmetical progression in a counter-clockwise direction as shown in Fig. 3, that is to say, the horizontal diameter of port, 30^a, is just twice the horizontal diameter of the oil tube, 80 26, of the corresponding nozzle. The horizontal dimensions of slotted port, 30^b, is just twice that of 30^a, and that of 30^c is three times that of 30^a, and that of 30^d, four times that of 30^a. Furthermore, it will 85 be noted that there is provided at the inlet to each nozzle, 24, a beveled channel, 26^a, leading to the oil tube, 26, and that these beveled channels, 26^a, progressively increase in length in a counter-clockwise direction, 90 as shown in Fig. 2, each beveled channel, 26^a, being one-half as long as the horizontal diameter of each corresponding port, 30. The purpose of these beveled channels, 26^a, is to provide a gradual cut-off of the oil flow 95 through each nozzle as the valve member, 17, is rotated in a clockwise direction, as indicated in Fig. 3. As will be seen from this figure, if the valve member, 17, be rotated a slight distance in a clockwise direction, 100 the oil tube, 26, of the nozzle opposite port, 30^a, will pass out of register with that port, leaving as a means of connection, the beveled channel, 26^a, which has a varying depth, the greatest dimension of which is at 105 its point of junction with the oil tube, 26, and slightly less than the diameter of said tube and diminishing to zero in the horizontal distance specified above. In this position of valve member, 17, it will be seen that 110 a decrease flow of liquid fuel will take place through the nozzle opposite port, 30^a and due to the larger dimensions of the other ports, 30, full flow is still maintained there-through. A further rotation of member, 17, 115 results in a complete cutting off of the nozzle opposite port, 30^a, at which point, the left-hand edge of nozzle opposite 30^b is just coincident with the left-hand edge of that port. A further rotation of valve member, 120 17, will now result in a similar gradual cutting out of a nozzle opposite port, 30^b, as that described for the nozzle opposite 30^a. In this manner it is seen that a continuous rotation of the valve member, 17, will finally 125 result in the complete cutting off of all of the nozzles in turn. This will require rotation of the valve member, 17, through an angle of about forty-five (45) degrees.

Referring now to Fig. 2, the air ports, 20, 130

are similarly designated 20^a, 20^b, 20^c, and 20^d, in a counter-clockwise direction so as to show their corresponding relation to the oil ports, 30. It will be noted that the ports 5 21, with which the ports, 20, coöperate, are all of the same size and equal to an angular opening of about forty-five (45) degrees, whereas, the ports 20 have a common vertical dimension but increase in horizontal 10 direction in arithmetical progression in a counter-clockwise direction as shown in Fig. 2. In this connection, it is noted that port, 20^a, is exactly equal to one of the ports, 21, or has a value of angular opening of about 15 forty-five (45) degrees. Port, 20^c, is three-fourths of the size of "d", 20^b is one-half the size of "d" and 20^d is one-fourth the size of "d". It is thus seen that by this arrangement a gradual cut-off of the air flow 20 through these ports is secured by means of rotation of valve member, 17, in a clockwise direction exactly similar to that described for the oil ports, 30. In other words, a fixed relationship is established between the 25 area of oil ports and air ports in register and this ratio remains constant throughout the opening or closing of the valves. The liquid fuel flow into the chamber 3, is regulated by a plug valve, 41, rotatably mounted 30 in a lug off-set from the casing, 1. This plug valve, 41, has two channels therethrough; a small channel, 43, adapted to register with oil supply pipe, 47, and an inlet duct, 44, when in open position and to 35 shut off connection between 47 and 44 when in a closed position, and a larger channel 45, which establishes connection between air supply pipe, 48, and conduit, 46, when in open position and to interrupt connection 40 therebetween when in closed position. Plug valve, 41, is rotated to open and close its ports by means of a lever-arm, 40, attached to a hollow metallic float, 39. The level of the oil in chamber, 3, is maintained at a 45 height indicated by the dotted line in Fig. 1. The arm, 40, is screwed into the plug, 41, and operates in a slot, 42, in the casing, 1, and it is noted that by this arrangement, the air and oil feeds are simultaneously controlled 50 by a single valve member. The oil supply pipe, 47, and air supply pipe, 48, both lead to the main fuel tank, 49, which is supplied with air under pressure by a supply pipe, 50, that leads from an air pump, 51, which is driven by the engine. This pump, 55, is of the small conventional plunger type operated by spur-gear, 52, geared to the engine and having an air intake port, 53, uncovered by the piston at each stroke, a check 60 valve, 55, and an overload relief valve, 54, of the spring-pressed puppet type. A dashboard air pressure gage, 56, may be attached at some point to the pipe, 50, to indicate to the operator the pressure at any time in the 65 main fuel tank, 49.

Fig. 9 shows an index pointer, 62 secured by means of screws, 63, to the wall of the casing, 1, said pointer having a beveled straight-edge, 64, to aline with index lines, 68, scratched in the face of index strip, 65, 70 which is secured to the lower outer periphery of cap, 7, in an adjustable position by means of elongated slots, 66, and screws, 67. The graduations, 68, on this index are in pounds and tenths of air to one of oil so that 75 the normal or mid-reading is 1:15 and the extreme left reading 1:14 and the extreme right reading 1:16. The graduation which alines with the beveled edge of 62 indicates the ratio, by weight, of liquid fuel to air at 80 that particular setting of the cap. For normal conditions, using a good grade of gasoline of .70 specific gravity, this index pointer would be set at normal or 1:15. If now, a lower grade of fuel is used having a 85 higher specific gravity and requiring a greater amount of air for its complete combustion, the cap would be given a slight rotation to the left, thereby bringing the pointer, 62, to some intermediate point as for 90 instance 1/15.2.

The operation of the device is as follows:

With the engine at rest, and the valve member 17, in a position one-eighth turn in a clock-wise direction, from that shown on 95 Figs. 2 and 3, handle, 61, is moved slightly in a counter-clockwise direction so as to just slightly open air port, 20^a, and oil port, 30^a, and the engine turned over. This results in an operation of the pump, 51, thereby bringing 100 pressure on the oil in tank, 49, and at the same time establishing a flow of air through supply pipe, 48, restricting channel, 45, conduit, 46, duct, 23, and nozzle, 24^a. At the same time, the piston 13, is in the position shown in Fig. 1, which is its lowermost position. The slight vacuum created 105 in the chamber above the piston, 13, causes the said piston to be slightly raised against the compression of the spring, due to the compressed condition of the air between the underside of piston, 13, and the liquid fuel, but such movement is very slight at this initial stage, and consequently, the liquid fuel is under a pressure almost equal to the 110 full force of the spring. This causes an energetic emission of the oil through tube, 26, of the only nozzle in register, and this oil emitting from tube, 26, meets at a point just inside the aperture, 28, with a surrounding 115 column of air under pressure whose source I have just indicated. This results in an 120 ejection of the liquid fuel from the nozzle, 27, in a fine spray or in a high state of atomization. This spray combines with the 125 air column entering through port, 20^a, is thoroughly mixed therewith in chamber 2, and carried up and through ports, 8', in member, 17, and out through outlet ports, 8, directly into the engine manifold, 8. As 130

the speed of the engine increases, the vacuum in the intake manifold is increased and this action on the top of piston, 13, causes it to be further retracted against the tension of 5 a portion of the spring 11, which in turn causes a lessening of the air pressure on the liquid fuel. A further increase in the speed of the engine will result in a further increase of the action just noted until a point is 10 reached where the piston has been so far retracted as to uncover the port, 16, and as long as this is maintained, the liquid fuel will be subjected to atmospheric pressure only. This condition corresponds to a state 15 of high speed of the engine and correspondingly greatest vacuum in the intake manifold.

The function and adjustment of the spring 11, will now be explained:

20 As was stated at the beginning of this specification, it is a well established though little known fact that gases, such as air, do not follow the same law of efflux as liquids, such as gasolene, and consequently for any 25 given degree of difference of internal and external air pressures, which difference will hereafter be referred to as effective pressure, a less weight of air per second will flow than gasolene, therefore, any device wherein the 30 air flow and liquid fuel flow is induced and controlled by one and the same effective pressure, cannot maintain any fixed ratio of flow between these two elements for varying degrees of effective pressure. This condition 35 of affairs is well illustrated by the curves in Fig. 8 of the drawings, and forming part of this specification. The equation for the construction of these curves is given on the chart Fig. 8 of the drawings and the nomenclature 40 is that adopted by Church in his "Mechanics of Engineering," Part II, Chapter VIII, on the "Kinetics of gaseous fluids," wherein—

P_n —is the external atmospheric air pressure;

45 P_m —is the absolute pressure prevailing in the mixing chamber of the carburetor, here taken to be equal to that in the intake manifold, since the two are in communication and have free and unrestricted connection.

50 γ_m is the weight of one cubic foot of air at the pressure and temperature of the atmosphere.

55 γ_m is the weight of a cubic foot of air at the pressure and temperature prevailing in the mixing chamber, here taken at thirty (30) degrees Fahrenheit, lower than that of the outside temperature.

60 μ is the combined coefficient of efflux for adiabatic flow and varies with the effective pressure according to the table of values given in paragraph 555 of Church's *Mechanics of Engineering*, for $d=.8''$. "G" is the rate of fluid flow in lbs. per sec.

65 μ_e is the combined coefficient of efflux corresponding to $\varphi=.97$ and $c=.6$, and is

constant. φ is the coefficient of velocity and "c" the coefficient of contraction of the liquid jet and these quantities, for the same liquid and under conditions of uniform flow, are sensibly constant, so that u_e is sensibly constant. F_m is the area of the air intake ports here equal to one-half square inch for half-throttle opening.

α is the ratio of internal and external pressure, P_m/P_n , expressed as a percentage.

70 With the quantities thus defined, curve No. 1 shows the variation in weight of liquid flow per second for varying values of α or effective pressure. This curve shows the true condition for liquid fuel flow for any 80 condition of vacuum existing in the mixing chamber from full atmospheric pressure down to seven pounds per square inch absolute. The scale of abscissæ for liquid flow is here taken as 1/15 of that for gaseous 85 flow so that a single curve will give true readings on each scale for an ideal mixture of 1:15.

Curve No. 1 is constructed from equation No. 1, which is known as the so-called 90 "water formula", and is true for liquids only.

Curve No. 2 is constructed from equation No. 2 and shows the variation in the weight of gaseous flow for the variations in value 95 of α or effective pressure. This curve is true for air or any gas but not true for liquids. The difference in abscissæ between these two curves shows a discrepancy between the actual flow of air (curve No. 2) 100 and the supposed flow of air (curve No. 1) when it is assumed to follow the law of liquid flow as in all suction-operative devices. It is seen that this discrepancy of flow increases uniformly from the value of 105 zero at a point of no effective pressure to a value of $c-b$ equal to .026 pound per second at a point where the effective pressure is 7.7 pounds per square inch or where the internal pressure is 7.— pounds per 110 square inch absolute.

Thus we see that the flow of air at this effective pressure should be .148 for an ideal mixture of 1:15 where, as a matter of fact, it is only .122 at this pressure while the 115 liquid flow is .0986, making the ratio a little over 1:12. This will show to what extent a single vacuum controlling the two flows fails to maintain the fixed ideal ratio of 1:15. A number of expedients have 120 been resorted to from time to time to correct for this discrepancy between the actual air flow and that demanded by theory to maintain an ideal mixture. The first of these expedients, herein called case 1, was 125 to set the needle valve controlling the liquid flow at such a point that the ideal ratio was obtained at low speed. Such a setting would be represented by curve No. 3^a, which is drawn parallel to curve No. 1, and inter- 130

sects the true air curve at a point *g*, where the value of *x* is 90 and the internal pressure 13.2 pounds absolute which corresponds to 350 to 400 R. P. M. of a standard four-cylinder engine. It is clearly seen that the liquid fuel flow following curve *g*—*h* intersects the curve *a*—*c* in but one point, *i. e.*, *g*, and at this point only is an ideal mixture obtained. Consequently, such a setting would give a mixture a little too thin at starting as is shown by the abscissa between curves No. 2 and No. 3^b at point *k*, and a mixture far too rich at normal high speed as is shown by the abscissæ *ch*, resulting in a waste of liquid fuel throughout all ranges of speed between points *g* and *h* and at the same time, a starting mixture slightly too lean. It is readily seen that such an operation is entirely unsatisfactory. Another expedient, herein called case 2, is represented by curve No. 3^b where the needle valve controlling the liquid fuel flow is set so as to give an ideal ratio of 1:15 at highest normal speed (point *c*) which gives satisfactory operation only at this speed and a mixture too thin at all slower speeds and culminating in a mixture so weak at starting as to be non-explosive, the discrepancy here being represented by the abscissæ at point *d*. The flow of liquid fuel in this case follows curve No. 3^b drawn parallel to No. 1 and through point *c*. Devices employing this means of adjustment, while more economical in operation than that described under case No. 1 and have to resort to the use of priming and strangling devices in order to get a mixture rich enough to start on. Such devices further are difficult of operation at the lower speeds as the mixture is seen to be too thin and any attempt to throttle down to low speed would invariably result in stalling. This arrangement is, therefore, unsatisfactory and a third expedient herein called case 3 more recent than the others just described is to set a needle valve so as to give an ideal mixture at starting (point *a*) and allow the mixture to increase in richness up to a certain point as for instance, point *e* and then dilute the mixture by bringing into action a secondary or auxiliary air supply. This gives rise to a sudden increase in the volume of air flow with no corresponding increase of effective pressure. Consequently, the curve of air flow following the curve No. 2 from point *a* down to *e* now extends in a horizontal direction from *e* to *f* and from *f* it resumes its original characteristic curve down to a point *b* where it again crosses the curve of oil flow, No. 1. Such an arrangement, it is seen, is some improvement over the other two as it gives an ideal mixture at three points, *i. e.*, at starting (*a*), at highest normal speed (*b*)

and one intermediate point where the horizontal line *e*—*f* crosses the curve No. 1, but how far even this arrangement fails to secure an ideal mixture throughout operating speeds is disclosed by the area *a*—*e*—*l* where the mixture is too rich, wasting liquid fuel and the area *l*—*b*—*f*, where the mixture is too thin, failing to get full power. Consequently, such an apparatus, while being a slight improvement over its predecessors, is far from being satisfactory.

So far as the applicant is aware, all devices now on the market employ one of these three types of apparatus. The applicant's idea is now to set the fuel valve so as to give an ideal ratio at highest normal speed (point *c*) as in case 2, and then to subject the liquid fuel to a progressively increasing positive pressure so as to raise the effective pressure controlling the liquid fuel feed by an amount represented by the ordinates between curves No. 3^b, and No. 2, so as to place the curve of actual liquid feed 3^b, upon the curve of actual air feed, No. 2, throughout its entire length, thus giving an ideal mixture at all operating speeds.

In this device this result is obtained by subjecting the fuel feed to atmospheric pressure at highest operating speed (point *c*) and then gradually increasing the pressure on the liquid fuel reservoir by means of the spring, 11, represented by the ordinate *d*—*a*, equal to approximately 1.9— pounds per square inch greater than atmospheric pressure.

Since the variation of positive pressure to be applied by the spring to the liquid fuel is not strictly linear, as is shown by the rate of increase of the ordinates between curves No. 2 and No. 3^b, from a point *c* to the ordinate *a*—*d*, the upper two or three turns of the spring, 11, would be given a temper sufficient to apply the slightly greater resistance necessary to obtain the exact variation required by the curves. The advantage of this apparatus is obvious as it gives an ideal mixture at all operating speeds. The exact adjustment of spring, 11, can be made from performance test by accurately setting the position of cap, 7, on casing, 1, and then securing it in the desired position by set screw, 9. The adjustment of the spray nozzle is readily made by turning the knurled head, 35, and securing the desired setting by lock nut, 37. The further advantage that this present apparatus obtains is the ability to handle liquid fuels of higher specific gravity due to the positive pressure feed and atomizing nozzles. A further advantage of a close regulation of the height of fuel in the reservoir and the elimination of a chattering float needle valve by the use of a rotary plug cut-off valve which regulates not only the

flow of liquid fuel into the reservoir, but also, at the same time, the flow of air to the nozzles, 24.

The diameter of pipe, 50, is made larger than that of 48, so that, notwithstanding the discharge of air through 48, pump, 51, will be able to maintain a positive pressure of at least two pounds per square inch in the main supply tank. This, it is noted is slightly in excess of the maximum pressure which the spring and piston, 13, can exert on the liquid fuel in the reservoir and consequently, the feed is maintained at all times into the reservoir so long as the cut-off valve, 41, allows communication. When the engine is run slowly and the volume of air delivered by the pump, 51, is necessarily reduced, the plug member, 41, will be rotated by the tendency of the fuel level to rise so as to restrict the passage of air through the pipe, 48, and channel, 46. By taking the supply of air for the nozzle from the main fuel tank, use will be made of whatever evaporation takes place therein, which evaporation is now lost through vent holes required to be left open in gravity supply tanks.

A further advantage of this pressure feed is that it enables the carbureter to be placed in any position desired with reference to the engine and supply tank, consequently, it can be placed directly between the two branches of the intake manifold and on a level with the intake ports so that a very small length of passage is traversed by the mixture after it leaves the carbureter and before it enters into the cylinders of the motor. This is a very desirable feature as it eliminates a large part of the condensation of the gasolene which now takes place in the long leads that are necessary for carbureters so positioned as to be fed by gravity from the main supply system.

It will be further noted that the opening of the air intake ports, 20 and 21, is effected simultaneously with a correspondingly proportioned opening of the liquid fuel ports so that the ratio of air to liquid fuel supplied is maintained constant throughout all the degrees of opening of the ports from minimum to maximum. I desire it to be understood that in the foregoing specification as well as in the appended claims the word "maintain" is used in its strictest sense, such as equivalent of holding or preserving in any particular state or condition. Since the complete control of the mixture is affected by means of the ports, 20 and 21, no butterfly throttle valve is necessary or contemplated for use in connection with this device, the control of the engine feed being directly affected by the operation of the handle 61.

I desire it to be understood that changes and modifications in the particular form of

the device illustrated in the drawings, as will appeal to those skilled in the art and falling within the scope of the appended claims may be made without departing from the broad principles of the invention.

What I claim is:

1. In a carbureter, a mixing chamber, an atomizing nozzle, an air supply and a liquid fuel supply thereto, and pressure means for regulating the liquid fuel supply so as to make said liquid fuel supply always bear a constant ratio to said air supply.

2. In a carbureter, a mixing chamber, an air supply and liquid fuel supply thereto, an automatic pressure means for regulating the liquid fuel supply so as to make said liquid fuel supply always bear a constant ratio by weight to said air supply.

3. In a carbureter, a mixing chamber, an air supply and liquid fuel supply thereto, and means to apply such a variable pressure to the liquid fuel supply as to make said liquid fuel supply enter said mixing chamber always in constant ratio by weight to said air supply.

4. In a carbureter, a mixing chamber, an air supply, and liquid fuel supply thereinto, and means to maintain such a pressure upon the liquid fuel supply as to always force said liquid fuel supply into said mixing chamber in constant proportion by weight to said air supply entering therein.

5. In a carbureter, a mixing chamber, an air supply, and liquid fuel supply thereto, and means for maintaining a variable pressure greater than atmospheric upon said liquid fuel supply so as to force said liquid fuel supply into said mixing chamber always in constant proportion by weight to said air supply entering therein.

6. In a carbureter, a mixing chamber, an air supply thereto, and means for supplying liquid fuel thereto under such a variable pressure greater than atmospheric as will always maintain a constant ratio by weight between the rates of flow of said air and liquid fuel supplies.

7. In a carbureter, a mixing chamber, and means for feeding liquid fuel thereinto, at a rate which varies in accordance with the law of adiabatic gaseous flow.

8. In a carbureter, a mixing chamber, a liquid fuel reservoir in communication therewith, and means for maintaining upon the liquid fuel in said reservoir such a variable pressure as will force said liquid fuel into said mixing chamber at a rate of flow which varies in accordance with the law of adiabatic gaseous efflux.

9. In a carbureter, a mixing chamber, and means for feeding liquid fuel thereinto under pressure greater than atmospheric, at a rate which varies in accordance with the law of gaseous flow.

10. In a carbureter, a mixing chamber, and means for feeding liquid fuel thereinto under a variable effective pressure greater than atmospheric and which varies directly 5 as the pressure in said mixing chamber.
11. In a carbureter, a mixing chamber, a liquid fuel reservoir in communication therewith, means for maintaining a pressure greater than atmospheric in said liquid fuel 10 reservoir and for varying said pressure directly with the pressure in said mixing chamber to force said liquid fuel into said mixing chamber in accordance with a predetermined variation of flow.
12. In a carbureter, a liquid fuel reservoir, means to maintain liquid fuel therein at a substantially constant level, an atomizing nozzle, means for supplying liquid fuel from said reservoir under a variable effective 15 pressure greater than atmospheric to said nozzle.
13. In a carbureter, a liquid fuel reservoir, means to maintain liquid fuel therein at a substantially constant level, an atomizing nozzle, means for supplying liquid fuel and air under a variable effective pressure greater than atmospheric to said nozzle.
14. In a carbureter, a liquid fuel reservoir, means to maintain liquid fuel therein at a substantially constant level, an atomizing nozzle, means for supplying liquid fuel and air under a variable pressure greater than atmospheric to said nozzle, and means 20 for automatically controlling said liquid fuel and air supplies.
15. In a carbureter, an atomizing nozzle, means for supplying liquid fuel and air under a variable pressure to said nozzle and a single means for automatically controlling 25 said liquid fuel and air supplies.
16. In a carbureter, a mixing chamber, a fuel feeding nozzle associated with the mixing chamber, means for supplying liquid fuel under pressure to the fuel feeding nozzle, means for supplying air under pressure to the fuel feeding nozzle, and an automatic 30 means for regulating the air supply and an automatic means for regulating the fuel supply to the fuel feeding nozzle.
17. In a carbureter, a mixing chamber, a fuel feeding nozzle associated with the mixing chamber, means for supplying liquid fuel under pressure to the fuel feeding nozzle, means for supplying air under pressure to the fuel feeding nozzle, and an automatic pressure means for regulating the 35 liquid fuel supply to the nozzle.
18. In a carbureter, a mixing chamber, a fuel feeding nozzle associated with the mixing chamber, means for supplying liquid fuel under pressure to the fuel feeding nozzle, means for supplying air under pressure to the fuel feeding nozzle, and an automatic 40 means for regulating and proportionately
- varying the air supply and an automatic means for controlling the liquid fuel supply.
19. In a carbureter, an atomizing nozzle, a liquid fuel reservoir, a liquid fuel supply tank, means for supplying air under pressure to said tank, means for conducting air and liquid fuel from said tank to said nozzle, and automatic means for regulating the supplies of air to said nozzle and liquid fuel to said reservoir.
20. In a carbureter, a mixing chamber, a liquid fuel reservoir, a liquid fuel supply tank, means for supplying liquid fuel and air under pressure to said tank, means for conducting liquid fuel from said tank to said reservoir, means for conducting air from said tank to said mixing chamber, and a single means for automatically regulating said liquid fuel and air supplies to said mixing chamber.
21. In a carbureter, a mixing chamber, a liquid fuel reservoir, a fuel feeding nozzle associated with the mixing chamber, means for maintaining a positive pressure upon the liquid fuel therein and for varying the pressure inversely as the vacuum in the mixing chamber, means for supplying liquid fuel under pressure to the liquid fuel reservoir, means for supplying air under pressure to the fuel feeding nozzle, a float in the reservoir, and valve mechanism for regulating the supply of liquid fuel to the reservoir and the supply of air to the fuel feeding nozzle, said valve mechanism being controlled by the float.
22. In a carbureter, a liquid fuel reservoir, means for supplying liquid fuel under pressure to the reservoir including a conduit, a fuel feeding nozzle, means for supplying air under pressure to the fuel feeding nozzle including a conduit, a float in the liquid fuel reservoir, and valve mechanism for the liquid fuel supply conduit and the air supply conduit controlled by the float.
23. In a carbureter, a liquid fuel reservoir, means for supplying liquid fuel under pressure to the reservoir including a conduit, means for supplying air under pressure to the fuel feeding nozzle including a conduit, a float in the liquid fuel reservoir, and a single valve device for regulating the liquid fuel supply through the liquid fuel conduit, and the air supply through the air conduit, said valve device being controlled by the float.
24. In a carbureter, a mixing chamber, a fuel feeding nozzle associated with the mixing chamber and comprising an outer air jet pipe and an inner liquid fuel tube, means for supplying air under pressure to the air jet pipe, and automatic means for supplying liquid fuel under a variable pressure greater than atmospheric to the liquid fuel tube.
25. In a carbureter, a mixing chamber, a

- fuel feeding nozzle associated with the mixing chamber and comprising an outer jet pipe and an inner liquid fuel tube, means for supplying air under pressure to the air jet pipe, means for supplying liquid fuel to the liquid fuel tube, and an automatic valve means for regulating and proportionately varying the supply of air and liquid fuel to the nozzle. 65
- 10 26. In a carbureter, a mixing chamber, a liquid fuel reservoir, a liquid fuel feeding nozzle associated with the mixing chamber, and comprising an outer jet pipe and an inner liquid fuel tube, means for supplying air under pressure to the air jet pipe, means for supplying liquid fuel under pressure to the liquid fuel tube, a float in the liquid fuel reservoir, and a single valve member for regulating the supply of air and liquid fuel 70 to the nozzle, said valve member being controlled by the float in the reservoir. 75
- 15 27. In a carbureter, a mixing chamber, a liquid fuel reservoir, a liquid fuel feeding nozzle associated with the mixing chamber, and comprising an outer air pipe and an inner liquid fuel tube, means for supplying air under pressure to the air pipe, means for supplying liquid fuel under pressure to the inner fuel tube, a float in the liquid fuel reservoir, and a single rotary valve member for regulating the supply of air and liquid fuel to the nozzle, said rotary valve member being operatively connected with the float. 80
- 20 28. In a carbureter, a mixing chamber, a plurality of fuel feeding nozzles associated with the mixing chamber, each fuel feeding nozzle comprising an outer air pipe and an inner liquid fuel tube, and an adjustable cap member for the air pipe, means for supplying liquid fuel to the liquid fuel tubes, means for supplying air under pressure to the air pipes, and means for simultaneously adjusting the caps of the air pipes. 85
- 25 29. In a carbureter, a mixing chamber, a plurality of fuel feeding nozzles associated with the mixing chamber, each fuel feeding nozzle comprising an outer air pipe and an inner liquid fuel tube, and an adjustable cap member for the air pipe, means for supplying liquid fuel to the liquid fuel tubes, means for supplying air under pressure to the air pipes, means for simultaneously adjusting the caps of the air pipes, said means comprising a stem mounted for rotation, a connection between said stem and each of the caps of the air pipes, and means for locking the stem in adjusted position. 90
- 30 30. In a carbureter, a mixing chamber, a plurality of fuel feeding nozzles associated with the mixing chamber, each fuel feeding nozzle comprising an outer air jet pipe, an inner liquid fuel tube, and a rotary adjustable cap member for the air jet pipe, means for supplying liquid fuel to the liquid fuel tubes, means for supplying air under pressure to the air jet pipes, means for simultaneously adjusting the caps of all of the air jet pipes, said means including a rotary stem, a head on the stem, and an arm on each of the caps of the air jet pipes operatively connected with said head. 95
- 35 31. In a carbureter, a mixing chamber, having an air inlet and mixture outlet, a liquid fuel reservoir, means for maintaining liquid fuel therein at a substantially constant level, and means for maintaining a positive pressure upon the liquid fuel in the reservoir, said means including a piston element in the reservoir acting to apply pressure upon the liquid fuel, said liquid fuel reservoir having communication above the piston element with the mixture outlet, the piston element being subject to the influence of the difference in air pressures existing in said mixing chamber and outside atmosphere. 100
- 40 32. In a carbureter, a mixing chamber having an air inlet and mixture outlet, a liquid fuel reservoir, means for maintaining liquid fuel therein at a substantially constant level, and means for maintaining a positive pressure upon the liquid fuel in the reservoir, said means including a piston element in the reservoir, a spring acting upon the piston to apply pressure upon the liquid fuel in the reservoir, the liquid fuel reservoir having a communication above the piston with the mixture outlet, the piston being subject to the influence of the difference in air pressures existing in said mixing chamber and outside atmosphere. 105
- 45 33. In a carbureter, a mixing chamber having an air inlet and mixture outlet, a liquid fuel reservoir, means for maintaining liquid fuel therein at substantially constant level, and means for maintaining a positive pressure upon the liquid fuel in the reservoir, said means including a piston in the reservoir acting to apply pressure upon the liquid fuel, and ports in the liquid fuel reservoir controlled by the piston to establish atmospheric pressure upon the liquid fuel in the reservoir. 110
- 50 34. In a carbureter, a mixing chamber having an air inlet and mixture outlet, a liquid fuel reservoir, means for maintaining liquid fuel therein at a substantially constant level, and means for maintaining a positive pressure upon the liquid fuel in the reservoir, said means including a piston in the reservoir, and a spring acting upon the piston to apply pressure upon the liquid fuel in the reservoir, the liquid fuel reservoir having communication above the said piston with the mixture outlet, the piston being subject to the influence of the difference in air pressures existing in said mixing chamber and outside atmosphere, and ports in the liquid fuel reservoir arranged 115
- 55 60 65 70 75 80 85 90 95 100 105 110 115 120 125

to be uncovered by the piston to establish atmospheric pressure upon the liquid fuel in the reservoir.

35. In a carbureter, a liquid fuel reservoir, 5 means for maintaining liquid fuel therein at a substantially constant level, and means for maintaining positive pressure upon the liquid fuel in the reservoir, said means including an adjustable cap member for the 10 reservoir, a piston element in the reservoir, and a spring interposed between the said cap and the piston, and acting upon the piston to apply pressure upon the liquid fuel in the reservoir.
- 15 36. In a carbureter, a liquid fuel reservoir, means for maintaining liquid fuel therein at a substantially constant level, and means for maintaining positive pressure 20 upon the liquid fuel in the reservoir, said means including an adjustable cap member for the reservoir, a piston element in the reservoir, and a spring interposed between the said cap and the piston, and acting upon the piston to apply pressure upon the liquid 25 fuel in the reservoir, and means for locking the cap in adjusted position.

37. In a carbureter, a mixing chamber, a liquid fuel reservoir in communication therewith, means for maintaining liquid fuel 30 in said reservoir at a constant level, means for maintaining a pressure greater than atmospheric upon said liquid fuel to force said liquid fuel into said mixing chamber.

38. In a carbureter, a mixing chamber, a liquid fuel reservoir in communication therewith, means for maintaining liquid fuel 35 in said reservoir at a constant level, a piston element and a spring acting upon a piston element to maintain pressure upon 40 said liquid fuel to force it into said mixing chamber.

39. In a carbureter, a mixing chamber, a liquid fuel reservoir in communication therewith, means for maintaining liquid fuel 45 in said reservoir at a constant level, a piston element and a spring acting upon the piston element to maintain pressure upon said liquid fuel to force it into said mixing chamber, and means for adjusting the tension of the spring.

40. In a carbureter, a mixing chamber, a liquid fuel reservoir in communication therewith, means for maintaining liquid fuel in said reservoir at a constant level and 55 means for maintaining a pressure greater than atmospheric upon said liquid fuel to force it into the mixing chamber, and means for varying the pressure upon the liquid fuel directly as the pressure in the mixing 60 chamber.

41. In a carbureter, a mixing chamber, a liquid fuel reservoir in communication therewith, means for maintaining liquid fuel in said reservoir at a constant level, means

for maintaining a positive pressure upon 65 said liquid fuel to force it into the mixing chamber and for varying the pressure upon said liquid fuel directly as the pressure in the mixing chamber, said means including a piston element.

70 42. In a carbureter, a mixing chamber, a liquid fuel reservoir in communication therewith, means for maintaining liquid in said reservoir at a constant level, means for maintaining a positive pressure upon said liquid fuel to force same into the mixing chamber, and means for varying the pressure upon said liquid fuel directly as the pressure in the mixing chamber, said means including a piston element and a spring 75 upon the piston element to apply pressure upon the liquid fuel.

80 43. In a carbureter, a mixing chamber, a liquid fuel reservoir in communication therewith, means for maintaining liquid fuel 85 in said reservoir at a constant level, means for maintaining pressure upon the liquid fuel in the reservoir, said latter means being subject to the influence of the difference of air pressure existing in the mixing chamber 90 and the outside atmosphere.

95 44. In a carbureter, a mixing chamber, a liquid fuel reservoir in communication therewith, means for maintaining liquid fuel in said reservoir at a constant level, means for maintaining pressure upon the liquid fuel in the reservoir to force said fuel into the mixing chamber, said latter means including a piston element subject to the influence of the difference between the air pressure existing in the mixing chamber and the 100 outside atmosphere.

105 45. In a carbureter, a mixing chamber, a liquid fuel reservoir in communication therewith, means for maintaining liquid fuel in said reservoir at a constant level, means for maintaining pressure upon the liquid fuel in said reservoir to force the liquid fuel into the mixing chamber, said means including a piston element and spring acting upon the piston to apply pressure upon the liquid fuel, said piston being subject to the difference between the air pressure existing in the mixing chamber and the outside atmosphere.

115 46. In a carbureter, a mixing chamber, a liquid fuel reservoir in communication therewith, means for maintaining liquid fuel in said reservoir at a constant level, adjustable means for maintaining pressure 120 upon the liquid fuel in the reservoir to force said fuel into the mixing chamber, said latter means including a piston element acting to apply pressure upon the liquid fuel in the reservoir, said piston being directly subject to the difference in air pressure existing in said mixing chamber and the outside atmosphere.

47. In a carbureter, a mixing chamber, a liquid fuel reservoir in communication therewith, means for maintaining liquid fuel in said reservoir at a constant level, 5 means for maintaining a positive pressure upon the liquid fuel to force said liquid fuel in the mixing chamber and for varying the pressure upon the liquid fuel directly as the pressure in the mixing chamber, and means 10 for establishing atmospheric pressure upon the liquid fuel when the pressure upon the liquid fuel is reduced to a predetermined degree.

48. A carbureter comprising, a liquid fuel reservoir with liquid fuel supply thereto, an atomizing nozzle with air supply and liquid fuel supply thereto, and a single means for regulating the supply of air to said nozzle and liquid fuel supply to said reservoir. 15

In testimony whereof I hereunto affix my signature in the presence of two witnesses.
